VALVE SILENCER

Paul L. Vermaire, Grand Rapids, Mich., assignor to
General Motors Corporation, Detroit, Mich., a corpora-
tion of Delaware

Application August 25, 1954, Serial No. 452,091

8 Claims. (Cl. 123—90)

This invention has to do with translating motion and taking up lash between driving and driven elements such as the operating cams and poppet valves of an internal combustion engine or the like. The invention is particularly directed to an improved valve silencer in the form of an articulated rocker assembly including a pivoted cam surfaced element through which the valve opening motion is transmitted and which has a weight acting thereon in conjunction with a spring to initially create a small lash and then take up the same between each valve operating cycle.

It is accordingly the object of the invention to provide a construction for accomplishing the aforementioned results which is simple in design and economical to manufacture, and will not get out of order in operation.

The means by which the invention may be carried out will be more readily understood from the following description of an illustrative embodiment thereof, having reference to the drawing wherein:

Figure 1 is a transverse sectional view through a portion of an internal combustion engine showing a poppet valve operating mechanism embodying the invention.

Figure 2 is an enlarged fragmentary view of Figure 1 with parts broken away and in section to show the features in better detail.

Figure 3 is an end view taken in the direction of the arrows 3—3 of Figure 4.

Figure 4 is an enlarged fragmentary view showing the valve operating mechanism in plan.

The engine illustrated in Figure 1 includes a cylinder block and crankcase 1 comprising one or more cylinders 2 fitted with pistons 3. Mounted in the cylinder head 4 in conventional manner is a poppet valve member 5 which is to be reciprocated between its closed position (shown) and a position downward thereof to effect the opening and closing of the combustion chamber port 6. The valve closing spring 7 reacts at one end against the cylinder head and at its other end through its connection to the valve stem 8 to close the valve. Opening of the valve against the force of this spring is effected by the rocker assembly 9, push rod 10 and an engine driven cam 11 whose motion is transmitted to the push rod through the tappet 12. The rocker assembly 9 includes a pivotally oscillated rocker member 13 journaled by a rocker shaft 14. One end 15 of the rocker member has the usual pivotal connection to the push rod afforded by the adjusting screw ball stud 16.

As best shown in Figures 2—4, the opposite end of the rocker 13 is provided with means for journaling a link 17 thereto for pivotal movement substantially in the plane of the rocker oscillation. Such means is shown in the form of a pin 18 extending across a bifurcation 19 and in slightly offset relation toward the rocker shaft from the valve stem axis. The link 17 has a depending portion terminating in a downwardly presenting cam surface 20 which is in engagement with substantially the center of the valve stem end face 21. As indicated by the angle A, this cam surface and end face are slightly divergent to each other when the parts are in valve closed position (shown in solid lines), which in combination with aforementioned offset of the pin 18 causes the link to pivot counterclockwise to the position shown in broken lines during valve opening. For this purpose the cam surface 20 can be made arcuate with its center of curvature at 22 which is eccentric to the axis of the pin 18 by an amount equal to that which

2

the pin 18 is offset from the valve axis in the "valve closed" position. As a result, during each valve opening action of the parts the downward motion of the valve is accelerated somewhat relative to the speed of the rocker movement and, vice versa, the valve movement is decelerated somewhat in the closing direction.

Disposed laterally of the pin 18 a substantial distance from the link 17 is an inertia hammer indicated generally by the numeral 25. As shown, this inertia hammer includes a bracket in the form of a stud 26 threaded or otherwise fixedly connected at one end to the link and extending therefrom in the direction oppositely of the rocker shaft 14 and perpendicularly to the pin 18. The stud terminates at its extended end with a head 27, and loosely mounted on the stud adjacent the head 27 is an annular weight 28. Between the bore of the weight 28 and the periphery of the stud 26 a clearance of the order of .02-.03 inch is provided, and spacing the weight 28 from the link is a sleeve 30. As indicated at 31 a substantial clearance likewise exists for freedom of movement of the weight on the stud between the head 27 and the sleeve 30.

Resilient means is provided for biasing pivotal movement of the link 17 about the pin 18 in the counterclockwise direction (as viewed in Figure 2). This resilient means is illustrated in the form of a coil compression spring 32 having its opposite ends located in suitable pockets provided therefor at 33 and 34 in the opposing faces of the link and bifurcation 19.

In operation, with each lift stroke of the engine cam 11 its motion is transmitted through the tappet 12 and push rod 10 to the rocker 13, causing it to pivot clockwise about its shaft 14 and force the link 18 in a downward direction to open the valve 5. In moving downward, the link is forced to pivot in a counterclockwise direction against the biasing action of the small spring 32. On the return or valve closing stroke, the valve spring 7 acts through the stem 8, link 17 and pin 18 to move their associated end of the rocker upward against the inertia of the inertia hammer 25. During this upward return movement, the weight 28 is therefore bearing on the upper side of the stud 26, all the clearance 29 having been taken up between the weight and that side of the stud. When the valve reaches its fully closed position (shown in Figure 1) and further upward movement of the stud momentarily ceases, the inertia of the hammer drives the stud further upwardly, with the result that the link 17 is pivoted counterclockwise against the biasing action of its spring 32. Such pivoting of the link while the valve remains stationary, in turn, causes the cam surface 20 of the link to disengage from the valve stem end face 21. The link spring 32, after overcoming the inertia force of the hammer, then forces the link to pivotally return in clockwise direction, taking up all lash in the valve operating mechanism.

Thus, the valve mechanism is readjusted each operating cycle to compensate for any expansion or contraction which may have occurred in the parts. The loose fit of the weight 28 on the stud 26 serves advantageously in this respect by delivering light impact loads to the link, sufficient to overcome frictional drag between rubbing surfaces of the various parts.

While my invention is shown and described with reference to only a single preferred embodiment, it is appreciated that various minor changes will readily suggest themselves to persons skilled in the art and which do not depart from the scope of the invention as defined hereinafter.

I claim:

1. In a motion translating and lash take-up connection including a pivotally oscillated member and a reciprocated member in alternate driving and driven relation with each other, a link connected for pivotal movement on said oscillated member and having a cam surface operatively engaging said reciprocated member, said cam surface having a curvature about an axis eccentric to said pivotal movement whereby movement of the reciprocated member is accelerated in the driven direction and is decelerated in the driving direction relative to the speed of movement of said oscillated member, a bracket ex-

3

tending from the link in a direction generally normal to said axis and carrying a weight adjacent its extended end tending to induce continued pivotal movement of the link after termination of each stroke of the reciprocated member, and resilient means acting between said link and oscillated member to bias their relative pivotal movement in the direction of maintaining engagement of said cam surface with the reciprocated member.

2. In a motion translating and lash take-up connection including a pivotally oscillated member and a reciprocated member in alternate driving and driven relation with each other, a link connected for pivotal movement on said oscillated member about a fixed axis thereon and having a cam surface operatively engaging said reciprocated member, said cam surface having a curvature about an axis eccentric to said pivotal movement whereby movement of the reciprocated member is accelerated in the driven direction and is decelerated in the driving direction relative to the speed of movement of said oscillated member, a bracket extending from the link in a direction oppositely of the pivotal axis of the oscillated member generally normal to said axis and carrying a weight adjacent its extended end tending to induce continued pivotal movement of the link after termination of each stroke of the reciprocated member, and resilient means acting between said link and oscillated member to bias their relative pivotal movement in the direction of maintaining engagement of said cam surface with the reciprocated member.

3. The invention defined by claim 2, in which said weight is loosely carried on said bracket whereby said continued pivotal movement of the link is accentuated by impacts transmitted through the bracket thereto by the weight.

4. In a rocker assembly for operating a poppet valve or the like, a rocker having an arm extending from the rocker axis and provided adjacent its extended end with means for pivotally carrying a link on an axis substantially parallel to the rocker axis, a link journaled to said means and having a depending portion terminating with a downwardly presenting valve engageable cam surface of arcuate shape whose axis is substantially parallel to and spaced oppositely of the rocker axis from said means, a spring interposed between said rocker and link biasing their relative pivotal movement in the direction of bringing said cam surface closer to the rocker axis, and an inertia hammer operative to deliver impact loads to the link for inducing its pivotal movement against the spring on completion of each valve operating cycle.

5. The invention defined by claim 4, wherein said inertia hammer comprises a weight disposed laterally of said means and a bracket supporting the weight, said bracket being connected to move with the link and said weight having limited freedom of movement relative thereto both in the direction about said means and toward and away therefrom.

6. In a poppet valve operating mechanism including a valve stem having an end face, a valve closing spring

connected to the stem, a rocker assembly operable against said end face to open the valve in opposition to the force of the closing spring, and driving means for the rocker assembly, said rocker assembly including a rocker having one end connected to said driving means and a link pinned to its opposite end for relative pivotal movement about an axis normal to the plane of oscillation of the rocker, said link having a cam surface normally in abutting contact with said stem end face and inclined thereto in a plane normal to said axis at an angle decreasing with pivotal movement of the link during the valve opening stroke, a stud fixed at one end to said link and extending therefrom in the plane of said pivotal movement, a head on the extended end of said stud, a weight loosely fitting the stud adjacent said head, and means on the stud loosely spacing said weight from the link.

7. In a motion translating and lash take-up connection including a pivotally oscillated member and a reciprocated member, a cam element movable on the oscillated member and drivably operating the reciprocated member in response to pivoting of the oscillated member in one direction, an inertia hammer carried by said cam element for inducing its movement out of operative engagement with the reciprocated member upon completion of each return stroke of the reciprocated member, and means resiliently opposing said hammer induced movement of the cam element.

8. In a rocker assembly for operating a poppet valve or the like, a rocker having an arm extending from the rocker axis, a cam element movably mounted on the extended end of said arm having a valve engageable cam surface, said cam surface being disposed relative to the rocker axis such that movement of the cam element during valve opening movement of the rocker effects a lengthening of the distance between the valve engageable portion of the cam surface and said end of the arm, a spring interposed between the cam element and rocker biasing their relative movement in the direction of bringing said cam surface closer to the rocker axis, and an inertia hammer carried by said cam element for inducing its movement against the spring in response to the rocker stopping its movement in the valve closing direction.
